BALL CATCHING AND THROWING DEVICE

Clinton V. Carlson, Minneapolis, Minn., assignor to
Cosom Industries, Inc., Minneapolis, Minn., a corpora-
tion of Minnesota

Application May 23, 1957, Serial No. 46,296

Term of patent 14 years

(Cl. D34—5)

Fig. 1 is a view in perspective of a ball catching and throwing device showing my new design;

Fig. 2 is a view in top plan;

Fig. 3 is a view in side elevation; and

Fig. 4 is a view in transverse section, taken on the line 4—4 of Fig. 3.

I claim:

The ornamental design for a ball catching and throw-
ing device, as shown.
